UNITED STATES PATENT OFFICE

CLARENCE W. WHITE, OF NORTH BENNINGTON, VERMONT, ASSIGNOR TO H. C. WHITE COMPANY, OF NORTH BENNINGTON, VERMONT, A CORPORATION

DESIGN FOR A DESK

Application filed November 20, 1931. Serial No. 41,790. Term of patent 7 years.

To all whom it may concern:

Be it known that I, CLARENCE W. WHITE, a citizen of the United States, residing at North Bennington, county of Bennington, State of Vermont, have invented a new, original, and ornamental Design for a Desk, fully described and represented in the following specification and the accompanying drawing, forming a part of the same, in which:

The essential feature of my new design is the edge beading as applied to the vertical and horizontal portions of the desk proper including the legs thereof, the horizontal top and the vertical end portions of the roll top.

I claim:

The ornamental design for a desk as shown and described.

In testimony whereof I have hereunto set my hand.

CLARENCE W. WHITE.
